(57) **CLAIM**

The ornamental design for a stage microphone, as shown and described.

DESCRIPTION

FIG. 1 is a top, front, and left perspective view of a stage microphone showing the new design.

FIG. 2 is a bottom, rear, and right perspective view thereof.

FIG. 3 is a front elevation view thereof.

FIG. 4 is a right side elevation view thereof.

FIG. 5 is a rear elevation view thereof.

FIG. 6 is a left side elevation view thereof.

FIG. 7 is a bottom plan view thereof; and,

FIG. 8 is a top plan view thereof.

Features of the stage microphone shown in broken lines form no part of the claimed design.

1 Claim, 4 Drawing Sheets
